UNITED STATES PATENT OFFICE.

QUARTUS B. HENDERSON, OF TORONTO, ONTARIO, CANADA.

SANITARY SANDAL.

Application filed June 7, 1923. Serial No. 643,924.

To all whom it may concern:

Be it known that I, QUARTUS B. HENDERSON, a subject of the King of Great Britain, and resident of the city of Toronto, county 5 of York, Province of Ontario, in the Dominion of Canada, have invented certain new and useful Improvements in a Sanitary Sandal, as described in the following specification and illustrated in the accompanying drawings, that form part of the same.

The principal objects of this invention are to devise a sandal particularly adapted for use in connection with baths or gymnasiums where it is desirable to protect the feet from 15 being soiled while passing from the bath or the dressing room, and which will fit snugly to the foot and will be easy to walk in.

A still further object is to devise a form of 20 sandal which will readily adapt itself to and still fit different sizes of feet.

The principal feature of the invention consists in forming the sandal with a tapering toe pocket portion and a free sole portion 25 of a material having a marked degree of elasticity permitting expansion to accommodate the foot.

In the drawings, Figure 1 is a perspective view of my improved sandal as worn upon 30 the foot.

Figure 2 is a plan view of the sandal.

Figure 3 is an enlarged cross section through Figure 1 on the line 3—3.

Figure 4 is a cross section through Figure 35 2 on the line 4—4.

The preferable form of sandal is herein shown as being formed with a sole portion 1 formed with lateral extensions 2 which are folded inwardly and secured in a longitudinal seam 3 to form a tapering pocket to receive the foot. The sole portion is extended past the portions 2 in the form of a tab or lug 4, which is folded back over the tapered toe pocket to close the toe end 45 thereof.

The form of the sandal may be altered to a considerable extent but the principal element is in the use of an elastic material which will allow the tapered toe pocket to 50 expand laterally when the foot is inserted thereinto.

The preferred material with which to accomplish the desired result is a tough, crêpe paper and the blank for the sandal is cut with the crinkled corrugations of the paper 55 running longitudinally, that is, lengthwise of the sandal. The crinkled form of the paper provides a flexibility which is extremely desirable, in fact it is this feature which makes the sandal of value and practical. 60

Naturally the sandals are not made in numerous sizes but because of the flexibility of the paper stock from which they are made, together with the tapering shape of 65 the toe pocket, different sizes of feet will fit into the pocket and find comfortable accommodation because the tapering sides conform to the general shape of the foot while the elastic material spreads around the minor 70 shapes such as the toe joints, thus holding the sandal snugly to the foot without undue pressure. Further, the elasticity enables the wearer to bend the foot without a binding effect which would occur with the use of a 75 non-elastic fabric.

Another important feature in connection with the use of the heavy crêpe paper is that the under part of the sole is rough and gives the wearer a good gripping contact 80 with a slippery floor. Further, the crinkled paper structure only touches the floor surface in spots, consequently the paper will not become wet in such a manner as to break. The crinkled paper also presents a very attractive appearance which, though a minor feature, is nevertheless existent. 85

What I claim as my invention is:—

1. A sanitary sandal having a sole portion and a tapering toe pocket, both formed of 90 inelastic material creased longitudinally to impart uniform lateral elasticity.

2. A sanitary sandal formed of a single sheet of crêpe paper stock having the corrugations running lengthwise, said sheet being shaped with side flaps at the forward end turned inwardly and secured together in a longitudinal seam and forming a toe pocket, said toe pocket being capable of lateral expansion to accommodate the shape 95 of the foot. 100

QUARTUS B. HENDERSON.
